Joseph G. Lamb, of Cincinnati, Ohio,
Assignor to
A. Bradley, of Pittsburgh, Pa.
Letters Patent No. 543, Dated Jan'y 25th 1853.

The schedule referred to in these Letters Patent and making part of the same

To all whom it may concern:

Be it known that I, Joseph G. Lamb, of Cincinnati, in the County of Hamilton, & State of Ohio, have invented or produced a new Design for Cooking Stoves, and I do hereby declare the following is an exact description and that the annexed drawings are a correct representation of the said Design - Front,

Figure I, is a front view of the stove, showing two panel doors with ornaments in their centres as shown, and on either side of them, ornamented panels, marked A, & the words "The union" over the doors -

Fig VI, is the base moulding around the front, upon the hearth & wings.

Fig VII, is the moulding around the bottom of the stove.

Fig VIII, is the border around the hearth and wings.

Fig IX, is moulding around the doors.

Fig X, corners of Stove.

Having thus fully represented & described the aforesaid Design, what I claim as new and my invention is the arrangement and combination of the herein represented ornaments, mouldings, panelings, & shapes into the above specified Design for cooking stoves, substantially as above shown.
